UNITED STATES PATENT OFFICE.

FLETCHER C. ROOD, OF WALLA WALLA, WASHINGTON.

FLUSHING MECHANISM.

Application filed September 1, 1920. Serial No. 407,375.

To all whom it may concern:

Be it known that I, FLETCHER C. Rood, a citizen of the United States, residing in the city of Walla Walla, county of Walla Walla, 5 and State of Washington, have invented certain new and useful Improvements in Flushing Mechanisms, of which the following is a specification.

My invention relates to flushing mechanisms of the general character shown and described in my co-pending application, Serial No. 337,222, and has for its principal object to simplify and make more practical a flushing mechanism of the character referred to. In my application above referred to, the mechanism is connected with and operated by the seat or the cover of a toilet. In this application, the mechanism is set into action by simply pressing a lever. The 15 mechanism will be clearly understood from the following description of one practical embodiment of my invention, taken in connection with the accompanying sheet of drawings, in which,

25 Figure 1 is a vertical sectional view through my improved flushing mechanism;

Figure 2 is a horizontal sectional view, taken on line 1—2 of Fig. 1;

Figure 3 is a horizontal sectional view 30 taken on line 3—4 of Fig. 1, and

Figure 4 is a view of a detail.

Referring now in detail to the drawings, my invention as here embodied, comprises an outer cylindrical casing, 1, connected at 35 its lower end with a suitable supply of water, under pressure, by means of a pipe, 2, and at its upper end, connected by means of the pipe 3, with a toilet, or other receptacle to be intermittently flushed or supplied with a quantity of water. An inner, smaller cylinder, 4, is suspended in the upper end of the main casing 1, as shown, with suitable gasket 5, interposed between its upper end and the cap, 6, of the outer casing. Said inner cylinder is closed at its lower end; and near its upper end is provided in its side with a series of holes, 7. 45 Adjustably mounted through the lower end of the inner cylinder 4, is a slotted screw 8, through which passes a rod, 9, provided at its upper end with a screw sleeve, 10, and at its lower end connected with a rack, 11, in mesh with a gear, 12, on a shaft, 13, one end of which has a bearing in a cross bar, 14, 50 in the outer casing, 1, as indicated, and the

outer end of which has a bearing through the side of said outer casing 1, as at 15, with packing means, 16, to prevent leakage. The outer end of said shaft 13, is provided with a lever, 17, whereby said shaft 13 and its gear, 12, may be turned, to operate the rack 11, and the rod 9, as will be clear from the drawing. A bearing roller, 18, is also mounted on the cross bar 14, and bears against the back of the rack, as shown. 65

Near the lower end of the outer casing, 1, is an annular flange or floor, 19, to the underside of which is attached a spider-like member, 20, having the floor, 21, and the short cylinder portion, 22. A valve disc, 23, 70 covers the underside of the opening through the floor, or flange 19, and is attached to the lower end of the rack 11, as indicated. The lower stem portion of said valve, 23, is provided with a piston-like member 24, 75 fitting and moving in the short cylinder member 22; said member 24 being provided with a cup gasket, 24', as shown.

Slidably mounted on the rod, 9, in the inner cylinder, 4, is a loose piston, 25, 80 adapted to be raised by inflowing water into the inner cylinder, through the slotted screw, 8, for a purpose hereinafter again referred to.

The use and operation of my invention, 85 as shown for illustrative purposes, may be briefly described as follows: The supply of water from the pipe 2, is shut out by the closed valve member 23, in the position shown. In order to set the device in operation for flushing, the lever 17 is depressed by hand. This turns the gear 12, moves the rack 11 and rod 9, and valve 23 down, thus allowing water to pass upwardly through the annular flange or member 19, up around 90 the inner cylinder 4, through the holes 7, and out through the pipe 3 at the upper end, to the toilet or receptacle to be flushed. Water also passes through the slotted screw 8, and lifts the loose piston 25, on the rod 100 9 until it engages with the screw sleeve 10, at its upper end, which operates to raise the rod, 9, the rack 11, and the valve 23 to closed position, as shown, and the action 95 is finished. 105

When the loose piston 25 has been carried above the holes 7 in the upper end of the outer casing 1, the full force of the water then acts on the loose piston 25 and is sufficient to lift the rod, 9, rack 11 and the 110

valve 23 into closed position, as shown in the drawing.

In order to prevent the valve 23 from closing too suddenly and thus causing a knock or other objection, the piston-like member 24 is provided, which moves in the short cylinder, 22, and operates to control the movement of the valve, rack and rod upwardly, as will be understood from the 10 showing in Fig. 1 of the drawing.

I have not shown my flushing mechanism in connection with a stool or other basin, but it is to be understood that it is connected at its upper end, by means of the 15 pipe 3 with the inlet to the stool or basin, and is intended to be practically noiseless on account of avoiding the gravity feed of water into the basin to be flushed.

I am aware that changes in the details can 20 be made in my invention as here illustrated, without departing from the spirit thereof, and I do not, therefore, limit my invention to the showing made, except as I may be limited by the hereto appended claims.

25 I claim:

1. In a flushing mechanism, in combination, an outer casing connected at its lower end with a supply of flushing fluid, means for connecting its upper end with the receptacle to be flushed, an inner casing in 30 the upper end of said outer casing and having means for admitting fluid to its upper end and to its lower end, a loose piston member therein adapted to be lifted by the water entering the lower end of said 35 inner casing, a valve in the lower end of the outer casing controlling the passage of water upwardly through said outer casing and to said inner casing, an operating rod 40 connected with said valve and extended into said inner casing, means on said rod adapted to be engaged by said loose piston as it rises for lifting said rod and said valve to closed position by the action of the water, 45 and means for opening said valve, substantially as described.

2. In a flushing mechanism, in combination, an outer casing adapted to be connected at its lower end to a water supply, 50 and at its upper end to the vessel to be flushed, a valve in the lower end of said outer casing for controlling the flow of water up into said casing, a rod connected to said valve and extended upwardly in said casing, an inner casing in the upper end of said outer casing and through which said rod extends, a loose piston in said inner casing adapted to be lifted by water, and means whereby said loose piston engages with 55 said rod and lifts it and said valve to closed position, and means for manually opening said valve at will, substantially as described.

3. In a mechanism of the character referred to, a casing connected to a source 60 of water supply, whereby water passes

through said casing, a valve seat and valve at the entrance end of said casing to control the admission of water thereto, means for manually opening said valve, means within said casing above said valve and connected therewith and adapted to be lifted by inflowing water for automatically closing said valve and shutting off said inflow, said means having a member adapted to settle by gravity in the water when the inflow is stopped, substantially as described. 70 75

4. In a mechanism of the character referred to, in connection with a water supply pipe, a casing interposed in said pipe, whereby water passes through said casing, 80 a valve for controlling the inflow of water, means for manually opening said valve at will, said valve being adapted to be held closed by water pressure thereagainst, an inner casing in said outer casing, a rod connected with said valve and extending into said inner casing, a lifting piston in said inner casing and adapted to be lifted by inflowing water, said lifting piston being adapted to engage and lift said rod and 85 said valve to closed position, and means whereby said lifting piston is acted on by the full force of the inflowing water as it reaches the upper limit of its movement in closing said valve. 90 95

5. In a mechanism of the character referred to, in connection with a water supply pipe, a casing interposed in said pipe, whereby water passes through said casing, 100 a valve for controlling the inflow of water to said casing, means for manually opening said valve at will, said valve being adapted to be held closed by water pressure thereagainst, a rod connected with said valve and extended up into said casing, an inner casing around said rod, a loose piston in said inner casing around said rod and adapted to be lifted by inflowing water and to engage and lift said rod and said valve to closed position, and means for controlling 105 the closing action of said lifting piston, substantially as described.

6. In a mechanism of the character referred to, a casing adapted to be connected into a water line to control the flow of water therethrough, a valve at the entrance end of said casing normally held closed by water pressure, means for manually opening said valve, means above said valve operated by inflowing water to automatically 110 close said valve, and means whereby the closing action is delayed until a quantity of water has passed through said casing. 115 120

7. In a mechanism of the character referred to, a casing adapted to be connected at one end to a supply of water and its other end connected with a discharge pipe, a valve in said casing for controlling the inflow of water thereto, said valve being held closed by the water pressure, means 125 130

for manually opening said valve to permit water to pass through said casing, an inner casing at the other end of said main casing, means whereby water from said main casing passes through said inner casing, a moving piston member in said inner casing and having operating connections with the valve in said outer casing whereby the movement of said piston member closes said valve, and means for regulating the quantity of water passing into said inner casing for operating said moving piston member, substantially as described.

8. In combination with a water pipe, a casing interposed therein, a valve therein adapted to be held closed by the water pressure thereagainst, means for manually opening said valve, said valve being adapted to remain open until moved closed, a rod connected with said valve and extended into said casing, an element slidable on said rod and adapted to be moved by water along said rod, and means for connecting said element to move said rod and said valve at the end of its movement, whereby said element automatically operates to close said valve.

9. In a flushing mechanism, a casing, a valve in said casing for controlling the flow of water therethrough, said valve being normally held closed by the water pressure, a rack and gear mechanism connected to said valve for positively moving the same to open position, a cylinder and piston connected with said rack, whereby the movement of said piston moves said rack to close said valve, said piston being moved by inflowing water in one direction and being adapted to settle by gravity when said valve is closed and the water supply is cut off, and means for controlling the amount of water admit-

ted to act on said piston, substantially as described.

10. In a flushing mechanism, a casing, a valve in said casing for controlling the flow of water therethrough, said valve being normally held closed by the water pressure, a rack and gear mechanism connected to said valve for manually moving it to open position, a cylinder and piston, the piston of which is connected for moving said rack to close said valve, means for admitting water to said cylinder to move said piston, and means for retarding the movement of said valve into closed position, substantially as and for the purpose described. 45

11. In a flushing mechanism, an outer casing, a valve therein for cutting off the inflow of water thereto, means for manually moving said valve to open position, means for retarding the closing movement of said valve, an inner cylinder in said casing, a rod connected with said valve and extending into said inner cylinder, a piston member movable on said rod within said inner cylinder, means for operatively connecting said piston to move said rod and said valve to closed position, and means for controlling the inflow of a supply of water to said inner cylinder to move said piston, said piston being adapted to settle by gravity after it has been moved by water to close said valve, substantially as described. 60 65

Signed at Walla Walla, Walla Walla County, Washington, this 24th day of August, 1920.
